DOOR LOCK FOR JALOUSIE DOOR

Robert S. Cline, Bradenton, Fla., assignor to V. E. Anderson Manufacturing Company, Bradenton, Fla., a corporation of Kentucky

Application April 2, 1956, Serial No. 575,528

16 Claims. (Cl. 189—46)

This invention relates generally to doors, especially jalousie doors, and refers more particularly to a lock and handle construction therefor.

It is an object of the invention to obtain a construction in which the lock is adapted for installation at the factory where the door is manufactured instead of being subsequently installed. It is a further object to obtain a handle construction for cooperation with the lock when thus installed. With these objects in view, the invention comprises a door stile, especially a metallic stile of U-shaped cross section, and a lock construction for fitting therewithin and positioned thereby. The invention further comprises a construction of inner and outer handle members also positioned by the stile in operative relation to the lock. The invention further comprises the more specific construction as hereinafter set forth.

Although the above described construction is primarily designed for use with metallic door stiles, it will be readily apparent that such construction can be used with the stiles or uprights of regular wood doors.

In the accompanying drawings:

Fig. 1 is a vertical section through the hollow stile showing inner and outer handle members attached thereto, and showing a lock mechanism within the stile between said handle members, parts being broken away and in section.

Fig. 2 is a cross section on line 2—2 of Fig. 4.

Fig. 3 is a sectional perspective view of a portion of the stile.

Fig. 4 is a vertical section on line 4—4 of Fig. 1.

Fig. 5 is a vertical section on line 5—5 of Fig. 1.

Figs. 6, 7 and 8 are cross sections respectively on lines 6—6, 7—7 and 8—8 respectively of Fig. 5.

Fig. 9 is a section on line 9—9 of Fig. 2.

The metallic door has elements thereof, including the stiles, formed of extruded bars. One stile A is of generally U-shaped cross section and has on its inner opposite faces narrow slightly projecting bearing strips A', A², the latter being at the open end of the U and having grooves A³ therein. To receive the lock and the handles, this stile A has a suitably positioned circular aperture A⁴ formed in the cross wall thereof and has apertures A⁵ in the opposite side walls, all centered in the same transverse plane. The apertures A⁵ have extension slots A⁶ at diametrically opposite sides thereof, and such slots A⁶ extend longitudinally of the stile A. There are also small apertures A⁷ in opposite side walls of the stile A, and such apertures A⁷ are spaced longitudinally from and are in vertical alignment with the slots A⁶.

The lock casing B includes a generally U-shaped member B' having a narrower portion B² adjacent to the cross portion B³ thereof. A complementary member C extends across the open end of the U-shaped member B' and is secured thereto by screws C'. Plates D corresponding in shape to the U-shaped member B' are positioned at opposite edges thereof and complete the enclosure. The

2

member C has formed thereon a circular boss C² which fits within the circular aperture A⁴ in the stile. An aperture C³ through this boss C² and member C receives the projecting portion of a slideable latch bolt F having a shank F' and the usual inclined face F².

E is a sheet metal stamping having right angle flange portions E' E² at opposite ends thereof. A slot E³ extends longitudinally centrally of the member E, and an enlarged circular hole E⁴ is provided in the flange E'. The hole E⁴ is adapted to receive the circular shank F' of the latch bolt F. The shank F' is provided with a peripheral groove F³ for receiving a snap ring G which retains the shank F' in engagement with the flange portion E' of the stamping E. H is a rock shaft extending across the casing B through the slot E³ in the stamping E and having circular end portions H' which engage aligned circular apertures D' in the plates D. The rock-shaft H has a projecting rock arm H² adjacent to one end thereof and is provided intermediate its ends with spaced grooves H³. I is a rod which has one end slidably engaging a recess F⁴ in the shank F'. At its opposite end the rod I has a bifurcated head I' provided with spaced flanges I² which straddle a non-circular portion H⁵ of the rockshaft H and are slotted to provide spaced fingers I³ that fit into the spaced grooves H³ in the rock-shaft H. A coil spring I⁴ is sleeved upon the rod I between the head I' thereof and a flange J² of an angle member J having a rearwardly projecting flange J' engaging a wider portion E⁵ of the slot E³. The flange J² is slotted at J³ to embrace the rod I and is normally held by the spring I⁴ against the rear end of the shank F' of the latch member F so as to be movable therewith. The flange J' engaging the wider portion E⁵ of the slot E³ in the member E inclines slightly upward as well as rearward from the lower end of the flange J². Adjacent its rear end the flange J' has opposite side edges slotted transversely at J⁴ to provide fingers J⁵ that are bent slightly downward. Inasmuch as the angle between the flanges J' and J² is slightly less than a right angle, the pressure of the spring I⁴ against the flange J² will cause the flange J' to incline slightly upward from the plane of the member E. Thus, in the assembled position of the parts, the latch bolt F, stamping E and angle member J are movable rearwardly as a unit in the casing B when the rockshaft H is turned anti-clockwise to cause the rock arm H² to exert a rearward force against the flange E² of the stamping E. During such rearward movement of the members F, E and J the rod I telescopes within the recess F⁴. However, such rearward movement is prevented if the rockshaft H is turned clockwise so that the rock arm H² is positioned in the rearward path of the flange J' projecting slightly upward from the slot E⁵ in the member E. The resilient pressure of the spring I⁴ will normally hold the latch member F projected from the aperture C³ in the boss C² and from the aperture A⁴ in the stile A. There is also a pin K extending across the narrow portion B² of the casing B, and pivoted on this pin K are a pair of bell crank levers K' spaced from each other by a tube K² on the pin. These levers K' perform a function which will be later described. The casing B is secured within the stile A by first engaging the boss C² with the aperture A⁴ of the stile A and then sliding a plate L in the grooves A³ to a position in registration with the casing B. A set screw L' in the plate L is then tightened to clamp the casing in this position where the axis of the rockshaft H passes through the centers of the apertures A⁵ in the sides of the stile. The handle M for the outside of the door is preferably U-shaped and is preferably formed as a die casting. The portion M' of the handle forms the hand grip thereof and the portions M² and M³ form supporting legs

and engage the stile A. The leg M² has a base portion M⁴ provided with a circular pilot portion M⁵ fitting the aperture A⁵. There is also a cylindrical recess M⁶ in the base portion M⁴ concentric with this pilot portion M⁵. A slideable cylindrical casing M⁷ telescopically engaging the recess M⁶ contains a rotatable key actuated tumbler type lock mechanism M²⁰ that is operatively connected to and is adapted to rotate a central shaft M⁸ of non-circular cross section. The shaft M⁸ engages a correspondingly shaped aperture H⁴ extending axially through the rockshaft H and is adapted to rotate this rockshaft H with it when actuated by the key. The casing M⁷ normally extends outward from the recess M⁶ and is resiliently held in this position by a coil spring M⁹ surrounding the central shaft M⁸ between an end plate M¹⁰ and the cross portion M¹⁹ of a U-shaped member M¹². This plate M¹⁰ bears against a spring ring M¹¹ engaging a groove in the base portion M⁴ surrounding the recess M⁶. In the present instance, the shaft M⁸ of non-circular cross section has a cylindrical portion M³⁰ rotatable in the cross portion M¹⁹ of the U-shaped member M¹² and is provided upon the outer side of said cross portion M¹⁹ with an integral disk or head M³¹ provided with a radially extending lug M³² adapted to be engaged by a lug M³³ projecting endwise from the rotatable tumbler type lock mechanism M²⁰ at one side thereof. Thus, when the lock mechanism M²⁰ is turned by a key, the lug M³³ will engage the lug M³² and will cause the head M³¹ and shaft M⁸ to turn. The U-shaped member M¹² has parallel arms M¹³ engaging channels M¹⁴ in the portion M⁴ at diametrically opposite sides of the recess M⁶ therein. The cross portion M¹⁹ of the U-shaped member M¹² is held by a split ring M²¹ within diametrically extending slots M⁴⁰ in the inner end of the cylindrical casing M⁷ so that when the latter is pressed in against the tension of the spring M⁹, the arms M¹³ will contact with the arms K³ of the bell crank levers K'. The other arms K⁴ of the bell crank lever K' contact with the inner face of the flange E² of the stamping E so that when the casing M⁷ is pressed inward the arms M¹³ will rock the bell crank levers K', thereby retracting the stamping E and associated members including the latch bolt F attached thereto. In brief, the casing M⁷ forms a push button which when pressed inward will retract the latch member F. The latch member F may also be retracted by turning the rockshaft H under the actuation of the key and through the medium of the shaft M⁸.

The handle N on the inside of the door is mounted in an elliptical shaped plate O having a pilot portion O' engaging the aperture A⁵ on the inner side of the stile A. This plate O and the outer handle M are secured to the stile A by clamping bolts O² which pass through apertures O⁴ in the elongated axis of the plate O, through the slots A⁶ in the stile A and into screw threaded recesses O⁵ in the inner face of the handle portion M⁴. The heads of these bolts O² are on the inside of the door so as to prevent unauthorized detachment of the outer handle M. This outer handle M is further secured by a bolt O³ extending through the apertures A⁷ in opposite side walls of the stile A. This bolt O³ has its head bearing against the inside of the stile A and has its threaded end portion M¹⁵ engaging a threaded recess M¹⁶ in the leg M³. The inner handle N has a horizontal portion N' provided at its outer end with a laterally extending integral lever arm portion N². The horizontal portion N' of the handle N has a reduced portion N³ extending through the plate O and secured thereto by a snap ring N⁴ that engages the plate O and a groove N⁵ in said reduced portion N³. There is also a central shaft portion N⁶ which is non-circular and fits in the central aperture H⁴ through the rockshaft H. This shaft portion N⁶ may be formed of a separate member having a knurled shank portion N⁸ driven into a central recess N⁹ in the horizontal portion N' of the member N. Thus,

if the horizontal portion N' is turned by the lever N², this will also turn the rockshaft H.

With the construction as above described it will be understood that the latch bolt F can be locked against retraction by turning the rockshaft H clockwise so as to move the rock arm H² into the rearward path of the angle member J. Such turning may be accomplished either by movement of the inner handle N through the medium of the shaft N⁶ or by the shaft M⁸ actuated by the key in the tumbler type lock mechanism M²⁰ in the cylindrical casing or push button M⁷. If it is desired to lock the door from the outside without using the key the inner handle N may be turned clockwise while the door is still open to position the rock arm H² in the rearward path of the flange J' of the angle member J. However, before the handle N is turned, the push button M⁷ must first be pressed inward so that when the rock arm H² is moved by the handle N to the position just mentioned said rock arm H² will ride over one of the downwardly bent fingers J⁴ onto the angle member J and consequently will press the flange J' downward, thereby rocking the angle member J against the resilient resistance of the coil spring I⁴. After the door is closed the push button M⁷ is released which permits the pressure of the spring I⁴ to move the members F, E and J outward until the angle member J clears the rock arm H², whereupon the flange J' of the angle member J will be sprung upward automatically by the pressure of the spring I⁴ into position to be obstructed by the rock arm H². In this position the arm H² will be in the rearward path of the flange J' of the angle member J and thus will prevent retraction of said members F, E and J. Thus the door cannot be opened from the outside except by the operation of the key. The door is opened from the inside by moving the handle N anticlockwise which causes the rock arm H² to engage the flange E² of the stamping E and move rearwardly the stamping E and associated members including the latch bolt F attached thereto. The lever N² is in locked position when it extends upward.

What I claim as my invention is:

1. In combination, a door stile of U cross section, a door lock casing within said U and having a boss engaging an opening in the cross wall thereof and constituting a sleeve for a slideable latch bolt, opposite side walls of said U being provided on their inner opposed faces at the open end of the U with longitudinally extending bearing strips having longitudinally extending grooves therein, and means holding said boss against displacement, including a slideable plate bridging the open end of the U at a point substantially in horizontal alignment with the opening in said cross wall and having edge portions engaging said grooves, and an adjustable element carried by said plate and engaging said lock casing.
2. In combination, a door stile of U cross section, a door lock having a casing inside said U and having handles upon opposite outer sides of said U, said casing having a boss extending through an opening in the cross wall of said U and constituting a sleeve for a slideable latch bolt, one of said handles and a mounting plate for the other of said handles having pilot portions engaging openings in opposite side walls of said U, and means for holding said boss and said pilots against displacement, including adjustable elements extending transversely of said stile and said lock casing and terminally engaging said one handle and the mounting plate for the other handle.
3. In combination, a door stile of U cross section, a door lock having a casing inside said U and having handles upon opposite outer sides of said U, said casing having a boss extending through an opening in the cross wall of said U and constituting a sleeve for a slideable latch bolt, a sheet metal stamping slideable within said casing and having two spaced flange portions, a latch bolt fixed to one of said flange portions and slidably engaging said boss, a rockshaft within said casing and having a rock arm engageable with the second of the flange portions of said stamping to retract said latch bolt, and means

for actuating said rockshaft, including shafts projecting from said handles through opposite side walls of said stile and telescopically but non-rotatively engaging said rockshaft at opposite ends thereof.

4. In combination, a door stile of U cross section, a door lock having a casing inside said U and having handles upon opposite outer sides of said U, said casing having a boss extending through an opening in the cross wall of said U and constituting a sleeve for a slideable latch bolt, a sheet metal stamping slideable within said casing and having two spaced flange portions, a latch bolt fixed to one of said flange portions and slidably engaging said boss, a rockshaft within said casing and having a rock arm engageable with the second of the flange portions of said stamping to retract said latch bolt, a pivotally mounted bell crank lever within said casing and also engageable with the second of the flange portions of said stamping to retract said bolt, means operable from one side of said stile for actuating said rockshaft, including a shaft projecting from one of said handles through one side wall of said stile and telescopically but non-rotatively engaging said rockshaft at one end thereof, means operable from the opposite side of said stile for alternately actuating said rockshaft and said bell crank lever respectively, including two independently operable members projecting from the other of said handles through the opposite side wall of said stile, one of said independently operable members being engageable with said bell crank lever, and the other of said independently operable members telescopically but non-rotatively engaging said rockshaft at the other end thereof.

5. In combination, a door stile of U cross section, a door lock having a casing inside said U and having handles upon opposite outer sides of said U, said casing having a boss extending through an opening in the cross wall of said U and constituting a sleeve for a slideable latch bolt, a sheet metal stamping slideable within said casing and having two spaced flange portions, a latch bolt fixed to one of said flange portions and slidably engaging said boss, a rockshaft within said casing and having a rock arm engageable with the second of the flange portions of said stamping to retract said latch bolt, a rod telescopically engaging said latch bolt and having a head straddling a part of said rockshaft intermediate the ends thereof, a coil spring sleeved on said rod between said head and said bolt and normally urging the latter to projected position, and means for actuating said rockshaft, including shafts projecting from said handles through opposite side walls of said stile and telescopically but non-rotatively engaging said rockshaft at opposite ends thereof.

6. In combination, a door stile of U cross section, a door lock having a casing inside said U and having handles upon opposite outer sides of said U, said casing having a boss extending through an opening in the cross wall of said U and constituting a sleeve for a slideable latch bolt, a sheet metal stamping slideable within said casing and having two spaced flange portions, a latch bolt fixed to one of said flange portions and slidably engaging said boss, a rockshaft within said casing and having a rock arm engageable with the second of the flange portions of said stamping to retract said latch bolt, a rod telescopically engaging said latch bolt and having a head straddling a part of said rockshaft intermediate the ends thereof, a coil spring sleeved on said rod between said head and said bolt and normally urging the latter to projected position, a pivotally mounted bell crank lever within said casing and also engageable with the second of the flange portions of said stamping to retract said bolt, means operable from one side of said stile for actuating said rockshaft, including a shaft projecting from one of said handles through one side wall of said stile and telescopically but non-rotatively engaging said rockshaft at one end thereof, means operable from the opposite side of said stile for alternately actu-

ating said rockshaft and said bell crank lever respectively, including two independently operable members projecting from the other of said handles through the opposite side wall of said stile, one of said independently operable members being engageable with said bell crank lever, and the other of said independently operable members telescopically but non-rotatively engaging said rockshaft at the other end thereof.

7. In combination a door stile of U cross section, a door lock having a casing inside said U and having handles upon opposite outer sides of said U said casing having a boss extending through an opening in the cross wall of said U and constituting a sleeve for a slideable latch bolt, a sheet metal stamping slideable within said casing and having two spaced flange portions, a latch bolt fixed to one of said flange portions and slidably engaging said boss, a rockshaft within said casing and having a rock arm engageable with the second of the flange portions of said stamping to retract said latch bolt, a rod telescopically engaging said latch bolt and having a head straddling a part of said rockshaft intermediate the ends thereof, a coil spring sleeved on said rod between said head and said bolt and normally urging the latter to projected position, said stamping having a longitudinally extending slot receiving said rockshaft, means cooperating with said rock arm to block retraction of said bolt including an angle member having a bifurcated part straddling said rod between said spring and said bolt whereby said angle member is movable rearwardly with said stamping and bolt upon retraction of said bolt, said angle member also having a rearwardly projecting second part engaging a portion of the slot in said stamping, said second part of said angle member having a downwardly inclined transversely extending finger, the construction and arrangement of said rock arm and said angle member being such that said rock arm is adapted when said bolt is projected to move to a position in the rearward path of the second part of said angle member to block retraction of said bolt and is adapted when said bolt is retracted to ride over said finger onto said second part so that when said bolt is thereafter returned by said spring from said retracted position to said projected position said rock arm will then automatically be in the position aforesaid to block retraction of said bolt, and means for actuating said rockshaft, including shafts projecting from said handles through opposite side walls of said stile and telescopically but non-rotatively engaging said rockshaft at opposite ends thereof.

8. In combination, a door stile of U cross section, a door lock having a casing inside said U and having handles upon opposite outer sides of said U, said casing having a boss extending through an opening in the cross wall of said U and constituting a sleeve for a slideable latch bolt, a sheet metal stamping slideable within said casing and having two spaced flange portions, a latch bolt fixed to one of said flange portions and slidably engaging said boss, a rockshaft within said casing and having a rock arm engageable with the second of the flange portions of said stamping to retract said latch bolt, a rod telescopically engaging said latch bolt and having a head straddling a part of said rockshaft intermediate the ends thereof, a coil spring sleeved on said rod between said head and said bolt and normally urging the latter to projected position, means cooperating with said rock arm to block retraction of said bolt, including an angle member having a bifurcated part straddling said rod between said spring and said bolt whereby said angle member is movable rearwardly with said stamping and bolt upon retraction of said bolt, said angle member also having a rearwardly projecting second part, the construction and arrangement of said rock arm and said angle member being such that said rock arm is adapted when said bolt is projected to move to a position in the rearward path of the second part of said angle

member to block retraction of said bolt, and means for actuating said rockshaft, including shafts projecting from said handles through opposite side walls of said stile and telescopically but non-rotatively engaging said rockshaft at opposite ends thereof.

9. In combination, a door stile of U cross section, a door lock having a casing inside said U and having handles upon opposite outer sides of said U, said casing having a boss extending through an opening in the cross wall of said U and constituting a sleeve for a slidable latch bolt, a sheet metal stamping slidable within said casing and having two spaced flange portions, a latch bolt fixed to one of said flange portions and slidably engaging said boss, a rockshaft within said casing and having a rock arm engageable with the second of the flange portions of said stamping to retract said latch bolt, a rod telescopically engaging said latch bolt and having a head straddling a part of said rockshaft intermediate the ends thereof, a coil spring sleeved on said rod between said head and said bolt and normally urging the latter to projected position, means cooperating with said rock arm to block retraction of said bolt, including a member straddling said rod between said spring and said bolt and movable rearwardly with the latter, said straddling member having a rearwardly projecting portion, said rockshaft being movable in one direction to cause said rock arm to engage the second of the flange portions of said stamping to retract said bolt and being movable in the opposite direction to cause said rock arm to be disposed in the rearward path of the rearwardly projecting portion of said straddling member to block retraction of said latch bolt, and means for actuating said rockshaft, including shafts projecting from said handles through opposite side walls of said stile and telescopically but non-rotatively engaging said rockshaft at opposite ends thereof.

10. In combination, a door stile of U cross section, a door lock having a casing inside said U and having handles upon opposite outer sides of said U, a slidable element within said casing and having two spaced flanges, a slidable latch bolt fixed to one of said flanges and projecting outwardly through aligned openings in said casing and stile, a rockshaft within said casing and having a rock arm engageable with the second of said flanges to retract said bolt, a rod engaging said latch bolt and having a head engaging a part of said rockshaft, a coil spring sleeved on said rod between said head and bolt and normally urging the latter to projected position, a member having a part between said spring and said bolt and movable with the latter, said rockshaft being movable anti-clockwise to cause said rock arm to engage the second flange aforesaid to retract said bolt and being movable clockwise to cause said rock arm to be disposed in the rearward path of said member to block retraction of said bolt, a pivotally mounted bell crank lever within said casing and also engageable with the second flange aforesaid to retract said bolt, a push button in one of said handles, means operable by said push button for actuating said bell crank lever to retract said bolt, and means operable by the other of said handles for actuating said rockshaft.

11. In combination, a door stile of U cross section, a door lock having a casing inside said U and having handles upon opposite outer sides of said U, a slidable element within said casing and having two spaced flanges, a slidable latch bolt fixed to one of said flanges and projecting outwardly through aligned openings in said casing and stile, a rockshaft within said casing and having a rock arm engageable with the second of said flanges to retract said bolt, a rod engaging said latch bolt and having a head engaging a part of said rockshaft, a

coil spring sleeved on said rod between said head and bolt and normally urging the latter to projected position, a member having a part between said spring and said bolt and movable with the latter, said rockshaft being movable anti-clockwise to cause said rock arm to engage the second flange aforesaid to retract said bolt and being movable clockwise to cause said rock arm to be disposed in the rearward path of said member to block retraction of said bolt, a rotatable key actuated tumbler type lock mechanism within one of said handles, means operable by said key actuated lock mechanism for actuating said rockshaft, and means operable by the other of said handles for actuating said rockshaft.

12. In combination, a door stile of U cross section, a door lock having a casing inside said U and having handles upon opposite outer sides of said U, a slidable element within said casing and having two spaced flanges, a slidable latch bolt fixed to one of said flanges and projecting outwardly through aligned openings in said casing and stile, a rockshaft within said casing and having a rock arm engageable with the second of said flanges to retract said bolt, a rod engaging said latch bolt and having a head engaging a part of said rockshaft, a coil spring sleeved on said rod between said head and bolt and normally urging the latter to projected position, a member having a part between said spring and said bolt and movable with the latter, said rockshaft being movable anti-clockwise to cause said rock arm to engage the second flange aforesaid to retract said bolt and being movable clockwise to cause said rock arm to be disposed in the rearward path of said member to block retraction of said bolt, a pivotally mounted bell crank lever within said casing and also engageable with the second flange aforesaid to retract said bolt, a push button in one of said handles, means operable by said push button for actuating said bell crank lever to retract said bolt, and means operable by the other of said handles for actuating said rockshaft.

13. In combination, a door stile of U cross section, a door lock having a casing inside said U and having handles upon opposite outer sides of said U, a slidable element within said casing and having two spaced flanges, a slidable latch bolt fixed to one of said flanges and projecting outwardly through aligned openings in said casing and stile, a rockshaft within said casing and having a rock arm engageable with the second of said flanges to retract said bolt, a rod engaging said latch bolt and having a head engaging a part of said rockshaft, a coil spring sleeved on said rod between said head and bolt and normally urging the latter to projected position, a pivotally mounted bell crank lever within said casing and also engageable with the second flange aforesaid to retract said bolt, a push button in one of said handles, a rotatable key actuated tumbler type lock mechanism within said push button, means operable by said push button for actuating said bell crank lever to retract said bolt, means operable by said key actuated lock mechanism for actuating said rockshaft, and means operable by the other of said handles for actuating said rockshaft.

14. In combination, a door stile of U cross section, a door lock having a casing inside said U and having handles upon opposite outer sides of said U, a slidable element within said casing and having two spaced flanges, a slid able latch bolt fixed to one of said flanges and projecting outwardly through aligned openings in said casing and stile, a rockshaft within said casing and having a rock arm engageable with the second of said flanges to retract said bolt, a rod engaging said latch bolt and having a head engaging a part of said rockshaft, a coil spring sleeved on said rod between said head and said bolt and normally urging the latter to projected position, a pivotally mounted bell crank lever within said casing and also engageable with the second flange aforesaid to retract said bolt, a push button in one of said handles, means operable by

15 5 10 15 20 25 30 35 40 45 50 55 60 65 70 75

said push button for actuating said bell crank lever to retract said bolt, and means operable by the other of said handles for actuating said rockshaft.

15. In combination, a door stile of U cross section, a door lock having a casing inside said U and having handles upon opposite outer sides of said U, a slidable element within said casing and having two spaced flanges, a slidable latch bolt fixed to one of said flanges and projecting outwardly through aligned openings in said casing and stile, a rockshaft within said casing and having a rock arm engageable with the second of said flanges to retract said bolt, a rod engaging said latch bolt and having a head engaging a part of said rockshaft, a coil spring sleeved on said rod between said head and said bolt and normally urging the latter to projected position, a rotatable key actuated tumbler type lock mechanism within said push button and provided at its inner end with an endwise projection, means operable by said push button for actuating said bell crank lever to retract said bolt including a slidably mounted member in said one handle interlocked with said push button and engageable with said bell crank lever, means operable by said key actuated lock mechanism for actuating said rockshaft, and means operable by the other of said handles for actuating said rockshaft.

16. In combination, a door stile of U cross section, a door lock having a casing inside said U and having handles upon opposite outer sides of said U, a slidable element within said casing and having two spaced flanges, a slidable latch bolt fixed to one of said flanges and projecting outwardly through aligned openings in said casing and stile, a rockshaft within said casing and having a rock arm engageable with the second of said flanges to retract said bolt, a rod engaging said latch bolt and having a

head engaging a part of said rockshaft, a coil spring sleeved on said rod between said head and said bolt and normally urging the latter to projected position, a pivotally mounted bell crank lever within said casing and also engageable with the second flange aforesaid to retract said bolt, a push button in one of said handles, a rotatable key actuated tumbler type lock mechanism within said push button and provided at its inner end with an endwise projection, means operable by said push button for actuating said bell crank lever to retract said bolt including a slidably mounted member in said one handle interlocked with said push button and engageable with said bell crank lever, means operable by said key actuated lock mechanism for actuating said rockshaft including a shaft rotatable in said slidable member and telescopically but non-rotatively engaging said rockshaft at one end thereof, and a head on said shaft and provided with a radially extending lug actuatable by the endwise projection aforesaid, and means operable by the other of said handles for actuating said rockshaft, including a shaft non-rotatively engaging said other handle and telescopically but non-rotatively engaging said rockshaft at the other end thereof.
